TOY SODA FOUNTAIN

Albert M. Steiner, Cincinnati, Ohio

Application March 8, 1950, Serial No. 8,398

Term of patent 7 years

(Cl. D34—15)

To all whom it may concern:

Be it known that I, Albert M. Steiner, a citizen of the United States, residing at Cincinnati, in the county of Hamilton and State of Ohio, have invented a new, original, and ornamental Design for a Toy Soda Fountain, of which the following is a specification, reference being had to the accompanying drawings, forming a part hereof.

Figure 1 is a front elevational view of the toy soda fountain, showing my new design.

Figure 2 is a side elevational view thereof.

Figure 3 is a cross-sectional view taken on the line 3—3 of Figure 1.

Figure 4 is a fragmentary cross-sectional view taken on the line 4—4 of Figure 1.

I claim:

The ornamental design for a toy soda fountain, substantially as shown.

ALBERT M. STEINER.
